5 Claims. (Cl. 5—247)

The present invention relates to a bed spring frame that may be used as bottom mattress.

Known spring frames comprise tension or compression springs which on being loaded or unloaded, give rise to clipping, binding or jamming actions which render necessary the mounting of protector means. A further disadvantage of such known spring frames is the fact that in use mostly the same springs are loaded which thus prematurely lose their resilience.

The spring frame disclosed herein comprises two lateral longerons or stringers which at uniform distances are interconnected by metal bars that are secured thereto in a non-twistable or non-torsionable relation, the bent-off end portions of said bars, which are bent substantially in the plane of the longerons, being detachably inserted in longeron bores extending substantially at right angles to the planes of the longerons.

Each single bar preferably comprises a circularly bent middle portion lying in a plane and laterally merging into extensions that are substantially parallel to each other, and the end portions being bent-off substantially at right angles to said extensions and said plane.

One form of my present invention is shown by way of example in the drawing, in which:

FIG. 1 is a top plan view and

FIG. 2 a side view of the spring frame,

FIG. 3 shows a vertical section through one of the two longerons,

FIG. 4 is a perspective view of one of the spring bars in larger scale, and

FIG. 5 shows a prop in elevation.

The bed spring-frame shown comprises two parallel longerons 1 and 2 which are interconnected through bars

3. Each of the bars 3 comprises a circularly bent middle portion 3a which on both sides merges into a straight portion 3b, and the end portions 3c are bent off. Middle portion 3a and the portions 3b are situated in one and the same plane, while the end portions 3c extend substantially at right angles thereto and are destined to be introduced into bores 14 provided in shoulderlike steps 4 of the longerons.

The equidistantly inserted bars 3 form the spring-bed proper, the bars being subjected to a resilient torsional stress through the eccentric bearing thereof when the bar middle portions 3a are being loaded. Such torsional resilience is still further enhanced in that the bar portions 3b butt against the outside surfaces of the steps 4 and cannot turn aside when the bars are loaded.

In place of the steps 4, rabbets may be provided in the longerons for receiving the portions 3b, which rabbets merge into bores for accommodating the end portions 3c.

The terminal bar 5 preferably does not comprise any straight portions so as to afford a support for the mattress to be laid on, up to the end of the longerons 1.

Two struts 7 are pivoted on pins 6 to the longerons 1 and are interconnected by circularly bent bars 3', as already described above. Since the straight portions of the bars 3' are positioned in rabbets, no substantially parallel bends thereof are required.

To make the struts 7 inclinable, which through the bars 3' are interconnected and which together form the so-called wedge, a bar configuration 8 (FIG. 5) is pivoted to that strut portion which is remote from the pins 6,

i.e. retained in eyes 11. When the struts 7 are inclined or raised, said configuration 8 is engaged in notches 9 of the longerons 1, 2. A handle portion 10 serves for lowering the configuration 8 and thereby the struts 7.

5 A sling 12 limits the travel or dislocation of member 8. If it is desired to lift individual bars from the longerons, the straight portions 3b of the bars have to be seized. To such end, the bars, as shown in FIGS. 3 and 4, in their straight portions 3b comprise a slight upward bulge immediately before the bend of the portions 3c, which allow to seize the portions 3b.

10 In place of the end angles 13 shown in the head part may be disposed—as shown in dash lines—a straight bar 13' of which the angularly bent bearing portion 13'b may be somewhat longer for stiffening purposes.

15 The spring frame described and shown is of simple manufacture and may be taken apart for transport and storage with a view of saving space. Nevertheless it represents a comfortable bottom mattress of which the

20 middle portion in particular affords a good springiness and which is very sturdy. Broken springs which may be caused by faults in the material, may be readily repaired. The frame may be raised after assembly by lifting the bars, for the bar end portion 3c thereby are tilted in 25 their bores and thus prevent the bars from being disengaged from the longerons.

25 The head part normally is made integral and undividable in that the bars 3' are fastly inserted in the struts 7. The head part, however, may be disengaged from the 30 pins 6 to reduce the weight of the entire frame. This is particularly desirable for lifting the frame from the bedsteads.

35 The two longerons 1, 2 do not comprise any special cross-members for completing the conventional frame, but the bars 3 assume such function. The entire frame is built up without helical springs nor screws so that the mattress accommodated thereon cannot be damaged by clamping, binding or jamming. Top or upper mattresses may be put down directly on the spring frame, without need for an intermediate protector means.

I claim:

1. A spring-frame for a bed, comprising in combination, two elongated substantially parallel frame members spaced apart from each other for a distance, and a series 45 of metal bars removably connected to, and thereby interconnecting, said frame members, each frame member having a series of bores in the longitudinal direction of said frame members, each bar comprising a middle portion and two parallel straight end portions extending in

50 one direction from said middle portion, and each end portion removably fitting into and engaging a bore, said middle portion being arcuate and in unloaded condition disposed substantially in a horizontal plane and said end portions disposed in a plane at right angle thereto, 55 whereby when a load is applied to the bed said bars will be stressed torsionally.

2. In a spring-frame, as claimed in claim 1, each bar comprising an extension between said middle portion and each end portion, said two extensions being substantially 60 parallel to each other.

3. In a spring-frame, as claimed in claim 2, each frame member having a vertically recessed section facing in the direction towards the other frame member, said bores being disposed in said sections, said straight extensions 65 bearing on said recessed sections.

4. In a spring-frame, as claimed in claim 2, each frame member including rabbets leading to said bores, said straight extensions being received in said rabbets.

5. In a spring-frame, as claimed in claim 1, together 70 with struts pivoted at one end to said frame members, and a rectangular member having a recessed handle

portion and being operable to brace said struts in selectively variable raised positions.
